LINING AND BEVELING MACHINE

Vernon Royle, Paterson, N. J.

Original application May 29, 1929, Serial No. 367,008. Divided and this application May 31, 1934, Serial No. 728,295

8 Claims. (Cl. 29—21)

This invention relates to a lining and beveling machine, primarily designed for the use of engravers, and has for an object to provide a machine in which the work clamp is arranged to be bodily adjusted across the table so that work having a substantially large area may be clamped throughout its length.

Another object consists in providing such a machine in which the alining gauge may be extended and adjusted across the table in position to coact with the work clamp.

A further object consists in providing certain improvements in the form, construction and arrangement of the several parts, whereby the above named and other objects may effectively be attained.

A practical embodiment of my invention is represented in the accompanying drawings, in which

Fig. 1 represents a side elevation of the machine;

Fig. 2 represents an elevation, partly in section, taken at right angles to Fig. 1;

Fig. 3 represents a plan view, partly broken away;

Fig. 4 represents a detail section taken in the plane of the line IV—IV of Fig. 1, looking in the direction of the arrows;

Fig. 5 represents a detail elevation of the table, clamp, and adjacent mechanism from a point of view opposite to that of Fig. 1;

Fig. 6 represents a detail plan view of the alining gauge and adjacent parts; and

Fig. 7 represents a detail elevation of the same.

This application is a division of my copending application filed May 29, 1929, Serial No. 367,008.

The machine includes a base 1 arranged to be held in position by suitable lag screws, or the like, 2. From the base uprises a pedestal 3 to which is pivotally secured, as at 4, a motor support 5, on which is mounted a motor 6 by means of bolts 7. This motor receives a belt 8 which is designed to actuate parts hereinafter described.

A bracket arm 11 is fixed to the side of the pedestal 3 projects upwardly therefrom in two angular directions, as clearly shown in Figs. 1 and 2. The upper end of the arm 11 carries a cross head 13 which is provided with two wheels 16 and serves as an anti-friction support for one side of a carriage 18 which is reciprocated during the operation of the machine. The other side of the carriage is supported by a V-shaped rail 19 that is secured to the pedestal by bolts 20.

The means for reciprocating the carriage 18 includes a hand wheel 21 which is fixed to a rod

22 that is journaled in a swinging bearing 23 which is carried by a bracket 24 fixed to the side of the carriage. The construction and operation of the parts thus set forth is clearly shown, described and claimed in the application above mentioned and further description is not deemed necessary since it forms no part of the present invention.

The table which directly carries the work is denoted by 49, and is secured to the carriage 18 by screws 50.

The clamp for securing the work to the table consists of a clamping member 60 which is substantially the same length as the table, and is mounted for vertical adjustment in ways 61, 62 that are disposed to slide on and project upwardly from the opposite ends of the table. The lower portion of the ways 61 and 62 are arranged to overhang the opposite edges of the table 49 and are provided with inwardly projecting tongues 61* and 62* respectively, of which the tongue 61* is arranged to slide in a groove 61** in one edge of the table, while the tongue 62* slides in a groove 62** in the other edge of the table. A spacing bar 63 connects the ways 61 and 62 and gives rigidity thereto while the tongues 61*, 62* are slidably held in their respective grooves in the opposite edges of the table. The face of the clamping member 60 is provided with a pair of racks 64 that are designed to mate with gears 65 fixed on a shaft 66 that is mounted in the ways 61 and 62. This shaft 66 has one end furnished with a worm gear 67 that meshes with a worm 68 fast on a shaft 69 that is vertically journaled in a lateral projection on the way 62 and is operable by a hand wheel 70.

It will thus be seen that the clamping member 60 is raised or lowered in a perpendicular straight line movement by turning the hand wheel 70 in one direction or the other, and it may be added that the under face of said clamping member is preferably fitted with a pad of leather, or the like, in order to avoid injury to the work, since the clamping member is adapted to engage the entire length of the work on the table.

The machine also includes means for bodily moving the ways 61, 62 carrying the clamping member 60 laterally across the table, and this means consists of a pair of threaded rods 71, each of which has one end mounted in bearings 72 fixed to opposite portions of the table 49. The threads on the said rods mesh with interiorly threaded sleeves 73 that are bolted to ways 61, 62. In order to actuate the rods 71, a shaft 74 is mounted in bearings 75 which depend from

bearings 72. Each end of the shaft 14 has a spiral gear 76 fixed thereto and said gears mesh with spiral gears 77 that are fixed on rods 71. A crank handle 78 is secured to an end of shaft 14, and it will be seen that the turning of the said crank handle will correspondingly turn rods 71 in the threaded sleeves 73 so as to feed the ways 61, 62 and connected parts, laterally across the top of the table and hold the ways in their adjusted position, as shown in dotted outline in Figs. 2, 3, and 5.

This means for thus moving the clamp laterally and holding the same with respect to the table facilitates the use of the machine on various occasions, particularly where a single plate containing a group of pictures is being worked upon and it is, for instance, desired to line the boundaries of the individual pictures disposed throughout the area of the plate.

It is desirable that there be provision for a slight vertical adjustment of the table with respect to the carriage in order to provide for variation in depth of cut accomplished by the tools, and this is satisfied by a wedge-shaped slide 79 that intervenes between an inclined ledge 80 at the rear of the carriage and the adjacent horizontal under surface of the table 49. The slide has a pair of slots 81 formed therein to accommodate screws 82 that are threaded into the carriage, and these slots permit longitudinal movement of the slide by means of a nut 83 that is threaded on a stud 84 which projects from the carriage. A rim 85 on the hub of said nut rides in a kerf formed in the side of the slide 79, whereby by turning movement of the nut 83 will move the slide in one direction or the other with respect to the carriage and table fixed thereto, with the result that the table may be given a slight vertical adjustment in relation to the carriage. This adjustment is permitted by springs 53 which are arranged on screws 50 that secure the table to the carriage as hereinbefore described.

The cutter head for the beveling and, if desired, channeling tool is of a well known and approved form. It is denoted by 86 and is mounted on a spindle 87 which is journaled in a bifurcated standard 88 that is carried on the upper part of pedestal 3. A pulley 89 is fixed to spindle 87 intermediate the arms of the bifurcated standard, and is intended to be embraced by belt 8 which leads from the motor, as hereinabove described. The tools in the cutter head 86 may be of any well known or approved form for the purpose in hand.

The machine also includes a head for a variety of lining tools, or the like, which is indicated generally by 94. The detailed construction and operation of this head for the lining tools appears in United States Letters Patent granted to me jointly with Vernon E. Royle, under date of May 22, 1917 and No. 1,226,912, so that the same will not be shown or described herein.

The said head is fixed on a slide 95 and has its side edges beveled, and is mounted in an under cut track 96 that is carried on a support 97, which is rotatably mounted on a stud 98 that projects laterally from the side of standard 88. This rotatable mounting enables the tool head 94 to be swung into operative position or swung upwardly and rearwardly to inoperative position. The top of one side of track 96 is formed by a separate piece marked 99 that is traversed by screw 100 which is threaded into the body of the track. Thus, the part 99 serves, under the influence of the screw, as a clamp to grip the edge of the

slide 95 and hold the tool head 94 in its desired adjusted position. In order to provide for very accurate adjustment of this part, a sleeve 101 is adjustably fixed to slide 95 by a screw 102 which is yieldingly held in any desired position by spring 103. The said sleeve 101 carries an adjusting screw 104 which is threaded therein and fitted to abut the track 96. A micrometer gauge 105 is provided on screw 104 for precise work.

It will be seen that, when it is desired to adjust the head 94, the screw 102 may be loosened and the slide 95 moved over the top of the table to approximately the desired position, at which point screw 104 will be in abutment with track 96. Screw 102 is then set, and the precise adjustment of head 94 accomplished by turning screw 104 that is provided with a micrometer gauge. When the exact adjustment is obtained, clamp screw 100 may be tightened to hold the parts firmly in position.

The lining tool, or the like, carried by the head 94 when in operation, is angularly disposed so that the line cutting can be done on the forward stroke of the table at the same time that the beveling is accomplished.

The machine is further equipped with an alining gauge which includes a slide 107 that has beveled side edges which are mounted in an under cut track 108 rotatably mounted on a boss 109 that projects laterally from an arm 110 which is cast integrally with a support 111 which is bolted to and projects from the side of pedestal 3. Said rotatable mounting of track 108 enables the gauge to be swung into operative position, as shown in Figs. 6 and 7 and into inoperative position, as shown in Figs. 2 and 3.

The forward end of slide 107 has a T-head 112, in the ends of which are fitted trunnions 113 that carry a frame 114 which supports a gauge proper 115. The latter is provided with the usual serrated edge to facilitate its use in exactly pre-determining the line to be cut on the work. A guard 116 is carried on the slide 107 and fitted to receive and cover the serrated edge of the gauge proper when the latter is not in use. This protection is obtained by swinging the frame 114 on the trunnions 113 until the gauge proper 115 rests in the guard 116.

The construction of the parts for permitting adjustment of the gauge is the same as that just described in connection with the cutter head 94 so that it will be sufficient merely to indicate the parts by number. The separate clamping member of the track is marked 117 and its screw 118. The sleeve on the track is denoted by 119, its clamping screw by 120, the spring for the latter by 121, the micrometer adjusting screw by 122, and the micrometer by 123. It will be understood that these parts are arranged and operated in the same way as the corresponding parts associated with the cutter head 94 and its slide 95. This provision for extensive as well as precise adjustment of the gauge across the top of the table proper co-operates with the adjustability of the work clamp 69, hereinabove described, to facilitate operation upon plates where it is desired to cut lines at a distance from the edges of the plates as, for instance, when a plate including a group of pictures is being operated upon. In order to prevent the gauge from striking a blow upon the table when it is swung into operative position, I provide a stop 124 which is carried by the track 108 arranged to engage an abutment 125 on the arm 110 when the gauge has reached 75

its operative position immediately above the table.

The operation of the various parts of the machine has been described in connection with setting forth their construction, so that it is not regarded as necessary here to restate the operation of the machine as a whole. It may, however, be noted that the construction and arrangement well adapts the machine for attaining the objects hereinabove outlined and others inherent in its construction, and that its design contemplates efficiency, accuracy and speed in operation, together with general adaptability for meeting the varying needs of this particular class of work.

15 It will be evident that various changes may be resorted to in the form, construction and arrangement of the several parts without departing from the spirit and scope of my invention; and hence I do not intend to be limited to the details 20 herein shown and described, except as they may be included in the claims.

What I claim is:

1. In a lining and beveling machine, a table for supporting the work, vertically disposed ways 25 mounted to slide on the opposite ends of the table, a clamp extending between said ways and vertically movable therein for engaging the entire length of the work on the table, and means for moving the ways simultaneously for adjusting the 30 clamp laterally across the table.

2. In a lining and beveling machine, a table for supporting the work, vertically disposed ways mounted to slide on the opposite ends of the table, a clamp extending between said ways and vertically 35 movable therein for engaging the entire length of the work on the table, means for moving the ways simultaneously for adjusting the clamp laterally across the table, said means including rotatable shafts journaled in the ends of 40 the table and coacting with the ways, and gear mechanism for actuating said shafts to move the ways and clamp.

3. In a lining and beveling machine, a table for supporting the work, vertically disposed ways 45 at opposite ends of the table, each of said ways having a tongue and groove engagement with the adjacent end of the table, a clamp extending between said ways and vertically movable therein for engaging the entire length of the work on the table, and means for moving the ways simultaneously for adjusting the clamp laterally across the 50 table.

4. In a lining and beveling machine, a table for supporting the work, vertically disposed ways 55 at opposite ends of the table, each of said ways having a tongue and groove engagement with the adjacent end of the table, a clamp extending between said ways and vertically movable therein for engaging the entire length of the work on the 60 table, means for moving the ways simultaneously for adjusting the clamp laterally across the table, said means including rotatable shafts journaled in the ends of the table and coacting with the

ways, and gear mechanism for actuating said shafts to move the ways and clamp.

5. In a lining and beveling machine, a table for supporting the work, vertically disposed ways at opposite ends of the table, each of said ways having a tongue and groove engagement with the adjacent end of the table, a clamp extending between said ways and vertically movable therein for engaging the entire length of the work on the table, means for moving the ways simultaneously for adjusting the clamp laterally across the table, said means including rotatable shafts journaled in the ends of the table and having screw threaded engagement with the ways, and gear mechanism for actuating said shaft to move 10 the ways and clamp.

6. In a lining and beveling machine, a table for supporting the work, vertically disposed ways at opposite ends of the table, each of said ways having a tongue and groove engagement with 20 the adjacent end of the table, an interiorly screw threaded sleeve carried by each of said ways, a clamp extending between said ways and vertically movable therein for engaging the entire length of the work on the table, means for moving the ways 25 simultaneously for adjusting the clamp laterally across the table, said means including rotatable shafts, each having one end journaled in the table and the other end being provided with screw threads adapted to coact with the threaded 30 sleeves on the ways, and gear mechanism for actuating said shafts to move the ways and clamp.

7. In a lining and beveling machine, a table for supporting the work, a clamp supported and moved vertically and horizontally on the opposite 35 ends of said table for engaging the work on the table throughout its entire length, means for moving the clamp laterally across the table, an alining gage pivoted on the machine and arranged to co-operate with the table and clamp, and 40 means for moving the gage across the surface of the table toward and away from the clamp, said means including two elements, one slidable within the other and an adjusting mechanism carried by one element and engaging the other. 45

8. In a lining and beveling machine, the combination with a movable table for supporting the work, a beveling cutter associated therewith, a graving tool holder carried by the machine and movable across the surface of the table, and a 50 graving tool in said holder, of a clamp vertically and horizontally movable on the table and supported by the ends of the table for engaging the plate throughout its entire length, and means for bodily moving the clamp and its supports laterally 55 across the table toward and away from the beveling cutter, whereby the graving tool holder and tool may be moved toward and away from the clamp in position for the tool to line one or more subjects disposed within the central area of the 60 plate.

VERNON ROYLE.
